UNITED STATES PATENT OFFICE

KENNETH E. BEMIS, OF GLENDALE, CALIFORNIA

DESIGN FOR A PASTE TUBE CAP

Application filed May 9, 1932. Serial No. 43,762. Term of patent 14 years.

To all whom it may concern:

Be it known that I, KENNETH E. BEMIS, a citizen of the United States, residing at Glendale, in the county of Los Angeles and State of California, have invented a new, original, and ornamental Design for Paste Tube Caps, of which the following is a specification, reference being had to the accompanying drawing, forming part thereof.

Fig. 1 is a bottom plan view.

Fig. 2 is a top plan view.

Fig. 3 is a side elevation.

Fig. 4 is a front elevation.

I claim:

The ornamental design for a paste tube cap as shown.

KENNETH E. BEMIS.
